INDUCTION FURNACE

Application filed May 7, 1930, Serial No. 450,342, and in Great Britain May 8, 1929.

Our invention relates to furnaces and more particularly to electric induction furnaces.

An object of our invention is to provide a relatively simple and easily manipulated template for defining a melting chamber in an electric induction furnace.

Our invention relates particularly to electric induction furnaces of the kind in which a crucible or lining is made by ramming a suitable sand or some other suitable granular refractory material between a template and the energizing coil, the template being afterwards heated to sinter the sand or other refractory material.

In manufacturing furnaces having linings of the kind just mentioned, it has been found that the forces exerted on the energizing coil by reason of the expansion of a tubular metal template and the sand, when heated, may strain the coil to an undesirably high degree, whereby it may fail ultimately because of either electrical or mechanical reasons.

In practicing our invention, which is designed to overcome the above mentioned difficulty, we provide a template within an external casing and an energizing coil located in granular refractory material within such casing, the template being made of relatively thin metal and of tubular shape in lateral section and provided with one or more inwardly folded portions which are readily deformable, so that they will yield when the template expands, as well as a slip cover member on the outside of each of such inwardly folded portions.

In the single sheet of drawings,

Figure 1 is a view, in vertical section, through an induction furnace embodying our invention,

Fig. 2 is a view, in horizontal section, taken on the line II-II of Fig. 1, and

Figs. 3, 4 and 5 are plan views of modified forms of templates embodying our invention.

Referring first to Figs. 1 and 2, we have there shown an external casing 11 which may be made of metal and which, while being shown as substantially circular in sec-

tion, may be of any suitable or desired shape. The casing 11 has a lining 12 of granular, highly refractory material, such as certain forms of zirconium sand, which is not only electric insulating but also heat conducting. 55

An energizing coil 13 is located in the lining 12 and includes a plurality of turns of an electric-conducting member, here shown as being substantially rectangular in lateral section and, while no terminals for the energizing coil are shown, it is to be understood that such are actually provided in a manner well known in the art. In order to better protect the conductor, constituting the plurality of turns of the coil 13, from the relatively high temperature obtaining in an induction furnace when operating to melt metals or alloys, we provide a tubular member 14 of solid electrical-insulating material, such as mica. 65

A template 16, which is shown as being substantially circular in lateral section, is located within the external casing 11 and the coil 13 and is of such radial dimensions as to permit of locating a relatively large amount of the refractory material 12 between its outer surface and the inner surface of the member 14 which is usually rammed into place. The template 16 may be provided with a bottom closure 17 which may be spot welded to the bottom edge of its tubular body portion at a relatively small number of places to permit the tubular wall to move slightly relatively thereto. 75

A cover 18 is made of a highly refractory molded material and may include a pouring spout 19 and cooperate with a plurality of annular layers 21 of molded refractory bricks to provide an adequate cover for the furnace. While we have shown a specific form of cover, we do not desire to be limited thereto as these details are shown for illustrative purposes only and constitute no part of our invention. 80

After the inner portion of the refractory lining 12 has been rammed into place between the casing 11 and the outer surface of the template 16, it is usually desired to sinter the inner portion of the refractory lining immediately adjacent to the melting chamber 95 100

22, and this is best effected by energizing the coil 13 to heat the template 16. It has been found that, if a substantially solid tubular template is provided, that is, a template the wall of which is unbroken, the template will 5 expand to an undesired high degree and endanger not only that portion of the lining located between it and the energizing coil, but may also damage the energizing coil. 10 Hence, we provide the template with one or more readily deformable portions, preferably by bending a portion or a plurality of portions of the thin metal inwardly, as is shown more particularly at 23 in Fig. 2 of 15 the drawings.

In order to prevent the initially loose refractory material from flowing into the recess in the template, we provide a slip-joint cover 24 which may be made of relatively 20 thin metal of substantially the same length as the template and have one of its edges welded to the template at a few spots.

Referring to Fig. 3 of the drawings, we have there illustrated a substantially cylindrical template 26 which is provided with a plurality of inwardly projecting portions 27, each recess thus constituted being covered by an outer metal member 28 of substantially the same length as the template 26 and having 30 one edge spot-welded to the outer surface of the template at a relatively few places. While the template 16 is illustrated as being discontinuous as to its peripheral continuity, we have shown the template 26 as having a 35 substantially continuous sheet metal wall shaped to include the inwardly folded portions and then having its abutting edges spot-welded at a plurality of places to hold the same in its original shape during the 40 ramming operation.

Referring more particularly to Fig. 4 of the drawings, we have there illustrated a polygonal tubular template 31 having inwardly folded portions 32 at certain of the 45 external angles and slip covers 33 of angle-bar shape, to cover the outside of the recesses formed by the inwardly projecting portions, in order to prevent the entrance of sand into these recesses during the early stages of 50 manufacture of the furnace.

Referring more particularly to Fig. 5 of the drawings, we have there illustrated a substantially circular template 36 having a readily deformable portion 37 of somewhat 55 different and more intricate shape than the one shown in Figs. 2, 3 and 4. A cover 38 is provided for the portion 37, as hereinbefore set forth for the other templates.

It will be noted that, if one part of the 60 periphery of the template be considered as substantially stationary, the other part thereof of immediately adjacent thereto and separated therefrom by the inwardly projecting, readily deformable portions may move to- 65 ward the other portion when the template is

heated, because of expansion caused by the heating resulting from the eddy currents generated therein when the energizing coil is connected to a suitable source of alternating-current energy.

Heating of the template is primarily effected to cause sintering of that portion of the lining immediately adjacent to the chamber, and it is, of course, desirable to get rid of this template, particularly so if metals 70 or alloys other than that from which the template is made are to be melted in the furnace chamber. It is, therefore, necessary only to continue the energization of the coil 13 and possibly to add other raw material 75 to be melted in the furnace chamber which will cause melting of the metal of the template 16 in due course, and it may thereafter be poured from the chamber 22, it being understood that suitable tilting means is provided in a manner well known in the art. 80 85

While we have illustrated a particular embodiment of furnace structure, we do not desire to claim this, as our invention is more particularly in the thin-wall metal template, 90 and various modifications may be made in the device embodying our invention without departing from the spirit and scope thereof, and we desire, therefore, that only such limitations shall be placed thereon as are imposed by the prior art or are set forth in the appended claims. 95

We claim as our invention:

1. A furnace including a casing having a granular lining of refractory material, a 100 tubular template located within, and in engagement with, the granular lining to effect sintering thereof when heated, readily deformable means embodied in said template to prevent the exertion of pressure against 105 said lining when expansion is caused by heat.

2. A furnace including an exterior casing having an initially-granular lining of refractory material, a tubular template within the lining for defining a melting chamber therein, said template including a portion which is readily deformable and a slip-joint cover therefor to preclude the template from so expanding, when heated, as to exert radial pressure against the lining. 110 115

3. An induction furnace including an external casing having an initially-granular lining of refractory material and an energizing coil embedded in the lining, a tubular template of relatively thin metal within the refractory lining for defining a melting chamber therein, said template having an inwardly-folded readily deformable portion to preclude excessive radial expansion of the template when heated by inductive effect 125 from the energizing coil to effect sintering of the inner portion of the lining adjacent to the melting chamber.

4. An induction furnace including an external casing having an initially-granular 130

lining of refractory material and an energizing coil embedded in the lining, a tubular template of relatively thin metal within the refractory lining for defining a melting chamber therein, said template having an inwardly-folded and readily deformable portion to preclude excessive radial expansion of the template when heated by inductive effect from the energizing coil to effect sintering of the inner portion of the lining adjacent to the melting chamber, and a cover for said inwardly-folded portion secured to the template.

5. An induction furnace including an external casing having an initially-granular lining of refractory material and an energizing coil in the lining, a tubular template of relatively thin metal and of polygonal shape in lateral section located within the lining for defining a melting chamber therein, said template having inwardly-projecting and readily-deformable portions at certain of the respective angles of the template to preclude excessive expansion of the template 20 when heated inductively by the energizing coil to effect sintering of the inner portion of the lining adjacent to the melting chamber, and covers for said respective inwardly-folded portions having one edge of each secured to the template.

In testimony whereof, we have hereunto subscribed our names this twenty-third day of April, 1930, and this twenty-third day of April, 1930.
